[57] **CLAIM**

The ornamental design for a belt buckle rack, as shown and described.

DESCRIPTION

FIG. 1 is a front elevational view of a belt buckle rack showing my new design;

FIG. 2 is a right side elevational view thereof, the side opposite being a mirror image;

FIG. 3 is a rear elevational view thereof;

FIG. 4 is a top plan view thereof;

FIG. 5 is a bottom plan view thereof;

FIG. 6 is a front elevational view of a second embodiment of the design of FIG. 1, the only differences being a decrease in width and the number of apertures.

FIG. 1

FIG. 2

FIG. 3

FIG. 6

FIG. 4

FIG. 5
